UNITED STATES PATENT OFFICE.

ADAM PROBOLA, OF CLEVELAND, OHIO.

DESIGN FOR A CLOTHES-HAMPER.

SPECIFICATION forming part of Design No. 25,158, dated February 11, 1896.

Application filed January 9, 1896. Serial No. 574,911. Term of patent 7 years.

To all whom it may concern:

Be it known that I, ADAM PROBOLA, a citizen of the United States, residing in the city of Cleveland, in the county of Cuyahoga and State of Ohio, have invented and produced a new and original Design for Clothes-Hampers, of which the following is a specification, reference being had to the accompanying drawing, showing the same, and consisting in a single perspective view, which is deemed all that is necessary to fully illustrate the design.

The essential feature of my design consists of a clothes-hamper A, tapered uniformly and evenly on all sides from top to bottom, so as to be perceptibly smaller at the bottom than at the top, and having an ornamental

panel or center-piece B on each side, relieved and decorated about its sides and top and bottom with a border which stands out all around beyond the said ornamental panel and gives effect to the design. The top C is slightly arched and has an ornamental center-piece D and a raised border E.

What I claim is—

The design for a clothes-hamper as herein shown and described.

Witness my hand to the foregoing specification this 3rd day of January, 1896.

ADAM PROBOLA.

Witnesses:

H. T. FISHER,
H. E. MUDRA.
